(74) Attorney, Agent, or Firm — iPA & iPM

(57) **CLAIM**

The ornamental design for a drawer unit, as shown and described.

DESCRIPTION

FIG. 1 is a perspective view from above of a drawer unit showing my new design, wherein the drawer unit is shown with an inner container sliding out of a housing;
 FIG. 2 is a perspective view of the housing;
 FIG. 3 is a perspective view from below thereof;
 FIG. 4 is a front view thereof;
 FIG. 5 is a back view thereof;
 FIG. 6 is a left side view thereof;
 FIG. 7 is a right side view thereof;
 FIG. 8 is a top view thereof;
 FIG. 9 is a bottom view thereof;
 FIG. 10 is a perspective view of the inner container;
 FIG. 11 is a perspective view from below thereof;
 FIG. 12 is a front view thereof;
 FIG. 13 is a back view thereof;
 FIG. 14 is a left side view thereof;
 FIG. 15 is a right side view thereof;
 FIG. 16 is a top view thereof;
 FIG. 17 is a bottom view thereof;
 FIG. 18 is a perspective view of the drawer unit with the inner container completely enclosed by the housing; and,
 FIG. 19 is a perspective view from below thereof.
